LIQUID DISPENSING APPARATUS

Frederick W. Sturm, Fort Wayne, Ind., assignor
to The Wayne Pump Company, Fort Wayne,
Ind., a corporation of Maryland

Application April 19, 1939, Serial No. 268,813

4 Claims. (Cl. 221—95)

This invention pertains to a liquid dispensing apparatus and more particularly to a construction thereof wherein the meter, air separator and registering assembly may be readily disassembled from said apparatus as a unit for test or other purposes.

It is an object of this invention to provide a liquid dispensing apparatus having a meter, air separator and registering mechanism assembly, which readily may be replaceable as such.

Another object of the invention is to provide a compact assembly comprising a meter, air separator and registering mechanism which readily may be applied to a liquid dispensing apparatus or readily may be operated as an assembly as for test purposes, separate from the liquid dispensing apparatus with which it is adapted for assembly.

Still another object of the invention is to provide a liquid dispensing apparatus which is adapted for manual operation and wherein a simple, inexpensive interlock may be provided for preventing dispensing of liquid from said apparatus subsequent to a dispensing operation until the register has been reset to a predetermined position.

A further object of the invention is to provide a liquid dispensing apparatus which is of rigid construction, but wherein the bracing mechanism for the separate units is simplified and reduced to a minimum.

With these and various other objects in view, the invention may consist of certain novel features of construction and operation as will be more fully described and particularly pointed out in the specification, drawings and claims appended hereto.

In the drawings, which illustrate an embodiment of the device and wherein like reference characters are used to designate like parts—

Figure 1 is a sectional elevation of a liquid dispensing apparatus provided with the mechanism embodying the invention;

Figure 2 is a sectional elevation corresponding to Figure 1, showing the liquid dispensing apparatus wherein the meter, air separator and register mechanism assembly have been removed;

Figure 3 is an elevation of the meter, air separator and registering mechanism assembly showing the same removed from the liquid dispensing apparatus;

Figure 4 is a side elevation of the supporting bracket for the assembly illustrated in Figure 3;

Figure 5 is an end elevation of the supporting bracket illustrated in Figure 4;

Figure 6 is a top plan view of the bracket illustrated in Figure 4;

Figure 7 is an enlarged sectional elevation of the delivery flow control valve provided in the interlock arrangement of the liquid dispensing apparatus illustrated in Figure 1;

Figure 8 is an enlarged sectional elevation of the valve construction illustrated in Figure 7, the same being taken substantially in a plane at right angles to the plane in which the section of Figure 10 is taken.

In the device illustrated, the liquid dispensing apparatus consists essentially of a base 10, for supporting the casing 12, the casing being of any particular outside configuration, the casing being made rigid by the internal vertical bracing members 14 and the transverse platform or supporting member 16 suitably secured as at 18 and 22 to the vertical bracing. A pump 20 of the rotary positive displacement type is suitably secured to the under side of the platform 16, said platform being secured to suitable braces of the casing as at 18 and 22, the pump being adapted to be operated by means of the pulley or gear 24 provided on the rotor shaft 26. The gear 24 is connected by means of the chain or belt 28 to the gear 30, said gear being pivotally mounted as at 32 on the bracket 34 suitably supported on the platform 16 and being secured thereto as at 36.

The shaft 32 is adapted to rotate with pulley 30 and is provided with the pulley or gear 38, the gear 38 being connected by the chain or belt 40 to the gear or pulley 42 pivotally mounted on the bracket 34 as by means of the shaft 44, the shaft extending outwardly of the bracket and being provided with suitable means to receive an operating member such as a crank for rotating the gear 42, which motion is transmitted to the pump operating gear 24 by the train described. A suitable slack adjuster 46 is pivoted as at 48 to the bracket 34 and adjusted so that means such as a roller 50 engages the chain 40 to take up any slack due to wear or other causes.

The pump 20 is provided with the inlet 52 adapted to be connected to a suitable source of supply not shown, the outlet side of the pump being connected to the pipe 54 provided with a coupling fitting 56. The coupling fitting 56 is adapted to engage and be secured to a corresponding coupling fitting 58 of the pipe 60 as at 62. The pipe 60 is connected to the inlet side of the air separator 64. The outlet side of the air separator is adapted to be connected to the inlet side 66 of the meter 68; the outlet side of the meter being provided with the pipe 70 having a cou-

pling fitting 12 thereon. The air separator is also provided with a return fitting 74 adapted to be connected to a return pipe 76 which in turn is adapted to be connected to the inlet side of the pump 20 as through the fitting 71.

The vent of the air separator is adapted to be connected to the vent pipe 78 through the fitting 79, said vent extending upwardly and exhausting through the atmosphere at the high point in the apparatus such as shown at 80. The meter is provided with the meter shaft 82 adapted to be rotated in accordance with the liquid passing therethrough and is operatively connected to the rotating shaft 84 of the registering mechanism 86, said registering mechanism being of a construction such as illustrated in Patent No. 2,149,609 to Lennart, granted March 7, 1939. The registering mechanism 86 is adapted to be supported on the bracket 88, the bracket comprising the depending body portion 90 having suitable reinforcing flanges or ribs 92, 94, 96, 98, 100 and 102 and being adjustably secured and supported as at 104 on the air separator 64 through the elongated apertures 106. The upper flange 108 of said bracket is provided with the spaced legs 110, provided with elongated apertures 112 for accommodating suitable securing means 114 whereby the registering mechanism 86 is adjustably supported on said bracket.

The registering mechanism is provided with the reset shaft 116 provided with the clutch 118, said clutch being engaged by the yoke 120 provided on the interlocking rod 122, said rod being provided with the spring 124, normally urging said clutch toward engaging position. The clutch is connected through the jack shaft 126 and suitable gearing 128 to the reset knob 130, the said gearing being supported through the bracket 132 secured to the bracket 134 provided on the vertical framing. The bracket 136 is also supported on the vertical framing and provides a support for the bracket 138 to which the lever 140 is pivoted as at 142, the lever 140 being adapted to be moved with the lever 144. The lever 144 is connected as at 146 to the rod 148, said rod being pivotally connected as at 150 to the arm 152 of the bell crank 154, said bell crank being pivoted as at 156 to the bracket 160 which is extended outwardly of the pump casing and provides a nozzle support. The arm 152 is adapted to be engaged by the push button 158, said push button being disposed above the nozzle support and the lever 162 preferably is disposed in an overlying relation to the push button 158, being pivoted as at 164 to the pump casing.

The bell crank 154 is also provided with the depending arm 166 adapted to be engaged by the push button 168 disposed below the nozzle support 160. The inwardly extending arm 170 of the bell crank is pivotally connected to the rod 172, said rod extending upwardly, being pivotally connected as at 174 to the bell crank 176 provided on the valve shaft 178 of the delivery flow control valve 180. The valve 180 is connected at its inlet side to the pipe 182, said pipe extending downwardly therefrom, being connected to the expansion valve housing 184 and through said housing to the coupling 186, which in turn is suitably connected to the coupling 12 as at 187. The outlet side of the valve is connected to the discharge pipe 188, which in turn is connected to a suitable sight gauge 190 to which the dispensing hose (not shown) is connected at 192, the other end of the hose being connected to the dispensing nozzle 194; 75 said nozzle is shown being supported from the

nozzle support 160, in which case the nozzle valve cannot be operated.

When in supported position the lever 162 is depressed inwardly, preventing movement of the push button 168 inwardly. The valve 180 is provided with the valve seat 196 for the valve member 198, said valve member being fixed to the shaft 178. The bell crank 176 is provided with one leg 200 to which the rod 172 is pivoted as at 174 as already described, the other leg 202 being pivotally connected as at 204 to the contractile spring 206, the opposite end of said spring being pivoted as at 208 to the valve housing. It will thus be seen that the spring forms a means of biasing said valve so that it may be snapped to either open or closed position, depending upon which side of the dead center, that is, on which side of shaft 178 the spring 206 is disposed.

The registering mechanism, air separator and meter are fixed through the base 209 as by the bolts 210 to the brackets 212 supported on platform 16 so that, together with the piping, these units are maintained in a rigid and fixed position, yet may be readily removed, as will be more fully described.

In operation of the liquid dispensing apparatus, assuming that the register has been set to a predetermined or zero position, the nozzle 194 may be removed from the support 160 and the push button 168 may be pushed inwardly, causing the push button 158 to be moved outwardly. Movement of the push button 168 inwardly also causes the rod 148 to be moved upwardly whereby the lever 140 compresses the spring 124, causing the clutch 118 to be moved to declutched position. The rod 172 is moved upwardly, moving the valve member 198 off its seat 196, causing the lever 202 to be moved until the spring 206 passes dead center, at which time the valve member 198 is quickly moved to fully open position. The crank (not shown) may then be rotated to cause rotation of the gear 42, which in turn causes operation of the pump 20 for causing liquid to be drawn from the source of liquid supply and dispensed through the nozzle 194 in the usual manner.

While the dispensing operation is taking place, the register cannot be reset by the knob 130 as the clutch 118 is open. After the dispensing operation the hose nozzle 194 may be replaced on its support 160, which causes the push rod 158 to be moved inwardly, releasing compression of the spring 124 and permitting the clutch 118 to be moved to clutched position, at which time the register may be reset. The rod 172 is also moved downwardly, causing the valve member 198 to be moved toward closed position, moving the lever 202 until the spring 206 passes dead center, at which time the valve will be snapped to closed position as illustrated in Figure 7.

Under certain conditions the authorities who from time to time test liquid dispensing apparatus may prefer to test the essential units at some place distant from the liquid dispensing apparatus. In many instances this is desirable on account of the complicated testing machines sometimes necessary to be used, and under those conditions, of course, it would be very undesirable to remove the entire liquid dispensing apparatus and send it to the point of test. With this in mind the present liquid dispensing apparatus is so designed that the measuring and indicating mechanism may readily be removed, suitably boxed, and sent to the point of test.

In this instance the drain plug of the valve fitting 184 is removed and the valve therein is

raised in order to drain the piping above the fitting 184. It is then possible to disconnect the coupling member 186 from the coupling member 72 by removing the bolts 187, after which the fitting 76 may be disconnected from the pump 20 and drained. The fitting 76 can then be removed from the coupling 74 of the air separator 64, and the vent pipe 78 can be removed from the coupling 79 of the air separator 64. The bolts 210 under the meter 68 are removed, releasing the fastening of the meter to the brackets 212 supported on the platform 16, and thereafter the fastening means 62 are removed from the coupling members 56 and 58. The entire unit, that is, the register, air separator and meter, can then be lifted bodily from the liquid dispensing apparatus, leaving the apparatus as shown in Figure 2, and said unit can be shipped to the desired place for testing.

When the unit is returned it may readily be replaced or installed by placing the unit in the liquid dispensing apparatus in a position that the set back shaft 116 is properly aligned with the gear mechanism 128 in order to permit the insertion of the jack shaft 126. The interlocking rod 122 is disposed so that it is back of the lever 140 which is readily accomplished, particularly if the hose nozzle is permitted to remain on the support 160. After that the gaskets are properly replaced between the flanges of the coupling members 72, 186, 56 and 58 and the securing means is applied to tightly fasten the coupling members together, it being understood, of course, that they will not be tightened until all of the fastening means is in place, including the fastening means 210 of the meter 68 to the brackets 212. The tubing is then all connected, that is, the tube 76 is reconnected to the air separator 64 and the pump 20, and the vent tube 78 is reconnected to the air vent of the air separator 64. The drain plug is then tightened in the member 184 and the apparatus is ready for operation.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In liquid dispensing apparatus, the combination of a casing having spaced, vertically extending supporting frame members, a transversely extending platform connecting said frame members, a pump disposed below said platform and supported thereon, the suction side of said pump being adapted to be connected to a source of liquid supply, the outlet of said pump being connected to a pipe extending to a point above said platform, an assembly readily removable from said casing including a meter, an air separator and registering mechanism carried by and supported on said platform, said separator being above said meter, said registering mechanism being above said separator, said separator having an inlet provided with a pipe adapted to be connected to said first named pipe, the outlet connection from said separator being connected to the inlet of said meter and forming a support for

said separator, a discharge pipe from said meter, supporting means interposed between and connected to said separator and registering mechanism whereby said registering mechanism is supported on said separator, a discharge line spaced laterally from said discharge pipe, and offset connecting means adapted to connect said discharge pipe and discharge line but readily removable therefrom.

2. In liquid dispensing apparatus, the combination of a casing having spaced, vertically extending supporting frame members, a transversely extending platform connecting said frame members, a pump supported thereon, the suction side of said pump being adapted to be connected to a source of liquid supply, the outlet of said pump being connected to a pipe, an assembly readily removable from said casing including a meter, an air separator and registering mechanism carried by and supported on said platform, said separator being above said meter, said registering mechanism being above said separator, said separator having an inlet provided with a pipe adapted to be connected to said first named pipe, the outlet connection from said separator being connected to the inlet of said meter and forming a support for said separator, a discharge pipe from said meter, supporting means interposed between and connected to said separator and registering mechanism whereby said registering mechanism is supported on said separator, a discharge line spaced laterally from said discharge pipe, and offset connecting means adapted to connect said discharge pipe and discharge line but readily removable therefrom.

3. A unit of the character described comprising a meter having an inlet and an outlet, air separating means having an inlet, an outlet and a vent, the outlet of said separating means being closely adjacent and connected to said inlet of said meter, a support provided on said separating means, registering mechanism secured to said support, and a meter shaft connecting said meter and said registering mechanism.

4. In liquid dispensing apparatus, the combination of a casing having spaced, vertically extending supporting frame members, a transversely extending platform connecting said frame members, a pump disposed below said platform and supported thereon, the suction side of said pump being adapted to be connected to a source of liquid supply, the outlet of said pump being connected to a pipe, an assembly readily removable from said casing including a meter, an air separator and registering mechanism carried by and supported on said platform, said separator having an inlet provided with a pipe adapted to be connected to said first named pipe, the outlet connection from said separator being connected to the inlet of said meter and forming a support for said separator, a discharge pipe from said meter, supporting means interposed between and connected to said separator and registering mechanism whereby said registering mechanism is supported on said separator, a discharge line spaced laterally from said discharge pipe, and offset connecting means adapted to connect said discharge pipe and discharge line but readily removable therefrom.

FREDERICK W. STURM. 70
